UNITED STATES PATENT OFFICE

JANVIER DE LOPATTO LOCKFORD, OF NEW YORK, N. Y.

DESIGN FOR AN AUTOMOBILE

Application filed December 5, 1931. Serial No. 41,977. Term of patent 7 years.

To all whom it may concern:

Be it known that I, JANVIER DE LOPATTO LOCKFORD, a citizen of the United States of America, residing at New York, in the county of Kings and State of New York, have invented a new, original, and ornamental Design for an Automobile, of which the following is a specification, reference being had to the accompanying drawings forming part thereof.

Figure 1 is a side elevational view,
Figure 2 is a top plan view, and
Figure 3 is a front elevational view.

I claim:

The ornamental design for an automobile
as shown.

JANVIER DE LOPATTO LOCKFORD.
